UNITED STATES PATENT OFFICE.

ARCHIBALD SHAW, OF RANDWICK, NEAR SYDNEY, NEW SOUTH WALES, AUSTRALIA.

WIRELESS-TELEGRAPH TRANSMITTER.

1,192,126.

Specification of Letters Patent.

Patented July 25, 1916.

Application filed June 29, 1912. Serial No. 706,638.

To all whom it may concern:

Be it known that I, ARCHIBALD SHAW, a subject of the King of Great Britain and Ireland, residing at Dutruic street, Randwick, near Sydney, in the State of New South Wales, Australia, have invented certain new and useful Improvements in Wireless-Telegraph Transmitters, of which the following is a specification.

10 My invention consists in a wireless telegraph transmitter. An alternating current generator wound and driven to produce about 500 cycles per second is used in the primary power circuit. I have used such 15 generators at much lower rates of current reversal but with inferior results. The generator current is stepped up in a transformer (closed core by preference) to a voltage of about 28,000. The exciting circuit 20 contains capacity and inductance and it includes a rectifying break or spark gap, which will be described hereinafter in greater detail. The exciting circuit is usually connected to the radiator, so as to energize it by "shock excitation," but the coupling may be inductive. It is unnecessary 25 that the exciting circuit and the radiator should be in syntony when coupled electrostatically or conductively. In practice, the 30 frequency of the exciting circuit is higher than the frequency of the radiator when coupled electrostatically or conductively. The constants of the exciting circuit are adjusted so that the condenser charges and discharges once in every half cycle of the primary current. The radiator constants are 35 adjusted with regard to the required wave length, and so as, as far as possible, to increase the radiating qualities at the expense 40 of the oscillating qualities thereof, the object being to enable the aerial to radiate as freely as possible the energy thrown into it by the exciting circuit, and to cause the exciting circuit to maintain excitation of the radiator 45 with unidirectional impulses following each other with extreme rapidity while the primary circuit is closed.

One of the electrodes of the rectifying break or spark gap is in the form of a flat 50 surface and the other in the form of a conical blunt nosed nozzle set at from one half inch to five-eighths of an inch therefrom depending on the voltage, through which nozzle a fine jet of a pure or a mixed gas—air being 55 used in practice—is forced under high pres-

sure so as to impinge squarely against the face of the flat electrode. The electrodes are best made of copper or silver, zinc showing a tendency to pit at the place of impact of the gas jet. The diameter of the gas passage is proportioned to the power of the transmitter, and is about one sixty-fourth of an inch in diameter in the case of a two K-W set; the pressure used is preferably about 110 pounds on the square inch, at which 60 point I have obtained maximum effect under the conditions hereinbefore described. The working pressure may be varied to some extent above or below about 110 pounds per square inch directly proportional to the 65 voltage in the exciting circuit. If a pressure approximating toward 150 pounds per square inch is used, the flash or blaze assumes another form and the beneficial effects sought are seriously minimized or no longer 70 obtained. At pressures substantially below 50 pounds per square inch the effect is so far minimized as to be of small working value if not practically useless, the unidirectional 75 character of the discharge being then affected or entirely lost. The discharge across the gap is characteristically different from the spark obtained between the fixed or relatively moving pencil or ball electrodes ordinarily used in the gap of an oscillating circuit; and it is not in the nature of an arc. Measurement of the current in the radiator 80 by ammeter shows, for any given energy in the generator circuit, a higher reading than is obtainable when the radiator is energized 85 by an oscillating feeding circuit containing a spark gap with solid pencil shaped or spherical electrodes, and hence a high efficiency of transmission is attained. In consequence of the extreme rapidity at which 90 the radiator is repeatedly excited while the sending key is closed, an effective wave train is produced notwithstanding that the individual waves are damped. The frequency 95 of the individual waves varies in practice 100 from one million to ten millions per second, depending on the construction of the exciting circuit and its values.

In the drawings Figure 1 is a sectional elevation of the spark gap apparatus as 105 used by me, Fig. 2 an enlarged scale sectional elevation of the electrodes, and Fig. 3 face end views of the electrodes. Fig. 4, 5 and 6 are diagrammatic views of complete transmitters.

Referring to Figs. 1 to 3: A is a case constructed of micanite or other suitable insulating material and fitted with a lift lid B; it is supported on insulators C and fitted 5 with leading-in insulators D and D' the detail construction of which is unimportant. E and F are portions of the exciting circuit, their terminals being connected to the stems G and H of the electrodes K and L. The 10 flat faced disk electrode L is fitted with a solid stem H which should be provided with a screw adjustment in the leading-in insulator to enable the operator to vary the length of the gap readily. The stem G of 15 the flat nosed cone nozzle electrode K is tubular, and it is connected by a rubber hose M to a source m of air or gas under the necessary pressure. N is a valve in the hose M. The forward end of the nozzle electrode K is coned externally. P is an axial hole in the electrode K. The two electrodes K and L are arranged in axial alinement so that the gas jet impinges squarely on the face of the flat electrode. Q is an inclosing 20 box of wood, supported on heavy insulating feet R. I and J are leading-in insulators in the box Q. The spent air or gas finds exit through the joints in the case A and the box Q. The noise of the break is damped by 25 these inclosures. The break is kept cool as a result of the absorption of heat by the expanding gas.

In Figs. 4 and 5: T is the radiator, shown 30 in the form of an aerial wire, t condenser in the exciting circuit, t' variable loading coil for tuning purposes, X earth, U variable inductance in the exciting circuit, m air or gas 35 pump, M pipe from pump m to gap electrode, V step-up transformer, W sending key, Y impedance coil, Z primary alternating 40 generator.

In the electrostatic and inductive forms 45 of the coupling shown in Figs. 4 and 6 the condenser t is common to both the radiator and the exciting circuit.

In the conductive coupling arrangement 50 shown in Fig. 5 it is necessary to provide a separate condenser t^2 in the radiator circuit, as the condenser t is not included therein. 55 In the inductive coupling arrangement shown in Fig. 6 the connection R of the earth line is variable on the inductance coil U, the connections S and S' of the exciting circuit to this coil U being also made variable; in this arrangement the radiator and the exciting circuit should be in 60 syntony.

An essential feature of the invention is 65 the employment of a gas blast at a pressure varying between about 50 pounds and 140 pounds per square inch and preferably about 110 pounds per square inch, more or less, directed through a fine axial hole in a tubular electrode against the face of a solid 70 electrode across the spark gap in the ex-

citing circuit, the tubular electrode being conical and blunt nosed, and the solid electrode formed with an approximately flat face.

Heretofore spark gap electrodes have 70 been proposed one of which has the form of a point or pencil directed toward the other, which latter is made with a plane surface, with the object of obtaining a unidirectional flow of sparks and preventing oscillatory 75 flow of current across the gap; and it has been a common practice to play a jet of air on a spark gap, to effect cooling and to prevent arcing. These methods do not produce a blaze or torrential flash of current such as 80 is produced when the electrodes are formed as a blunt nosed cone and a flat plate with a needle jet of gas at pressure of 110 lbs. per square inch more or less passing through the cone electrode and directed axially from 85 the point thereof onto the flat face of the plate electrode. In the case of the arrangement used by me a very large volume of 90 energy passes over a short gap, which offers, other things being equal, minimum resistance, and this energy displays itself in the 95 exciting circuit in the form of unidirectional impulses of high frequency which may be transmitted as a train of damped waves. With any material difference in the shape 100 or arrangement of the electrodes or in the gas pressure the characteristic effects described are either procured indifferently or irregularly or entirely lost, and the volume of energy which can be employed usefully in the transmitter is of a relatively 105 lower order.

The operation is as follows:—The alternator Z delivers current at a periodicity of 110 per second, and when the sending key W is closed this current is stepped up in the transformer V to a voltage of about 28,000, charging the condenser t . Air is fed to the gap electrode K in the exciting circuit through the hose M from the pump m under a pressure of 110 lbs. per square inch. If the voltage in the exciting circuit is substantially over or under 28,000 a proportionately greater or less pressure is used. The values in the exciting circuit are proportioned so that the condenser t will charge and discharge once in every half cycle of the primary current. The radiator T is constructed to radiate freely in the frequency required for transmission, tuning being effected by means of the variable loading inductance t' . The condenser discharges 115 across the gap K—L in one direction only and feeds the radiator T with impulses of 120 great rapidity.

In the arrangement shown in Fig. 4 the coupling is electrostatic, in Fig. 5 conductive, and in Fig. 6 inductive but in each case the frequency of the radiator is determined by its own constants, and the frequency of 125

the exciting circuit is proportioned to the frequency of the generator.

Throughout this specification I have, in deference to established usage, employed the term "spark gap" referring to the gap in the circuit across which the condenser discharge jumps. It will be understood, however, that the operation of the device and the appearance of the discharge are not at all like those usually observable, the appearance, at the gap, being rather in the nature of a blaze or flash of light.

What I claim as my invention and desire to secure by Letters Patent is:—

1. In a wireless telegraph transmitter, the combination, with a primary circuit including a source of alternating currents, of a radiator exciting circuit including a condenser and proportioned to fix its charging and discharging period in correspondence with the period of reversal of the primary alternating current and containing electrodes in the form of a blunt nosed cone and a flat plate, with a short intervening gap between them, said cone electrode having a hole through it directed toward the plate electrode, in combination with means for forcing a needle jet of gas under a pressure of approximately 110 lbs. per square inch through said hole.

2. In a wireless telegraph transmitter including a source of high potential alternating current in a primary circuit, the combination with an exciting circuit coupled to a radiator and connected to said source of alternating current and proportioned to be charged and discharged once every half cycle of the primary alternating current, of a short gap in said exciting circuit the electrodes of which gap are respectively a blunt nosed cone and a flat plate, said cone being pierced with a hole, and means for forcing gas through said hole under a pressure approximating to 110 lbs. per square inch squarely against the face of said flat electrode.

3. In a wireless telegraph transmitter, the combination of a primary circuit including a primary source of high tension alternating current, a free radiator which is a poor oscillator and has its values proportioned to the transmitting wave length, an exciting circuit feeding said radiator on the shock excitation principle, said exciting circuit proportioned to be charged and discharged once every half cycle of the primary alternating current and having a gap the electrodes of which are located at a relatively short distance apart and consist respectively of a flat plate and a blunt nosed cone, means for forcing a needle jet of gas through a hole in said cone electrode under a pressure of approximately 110 lbs. per square inch against the face of said flat plate electrode, said source of high tension primary

alternating current of high initial periodicity energizing said exciting circuit, and a sending key in the primary circuit.

4. In a wireless telegraph transmitter, a radiator exciting circuit and a primary circuit inductively connected thereto, said primary circuit including a source of alternating electro-motive-force, said exciting circuit including a condenser and proportioned to fix its charging and discharging period in correspondence with the period of said source, a rectifying spark gap in said exciting circuit, an aerial connected to one side of said condenser, and means including a variable inductance for connecting said aerial to the ground.

5. In a wireless telegraph transmitter, the combination with a step-up transformer having in its primary circuit a source of alternating electro-motive-force and a sending key, of a rectifying spark-gap in the secondary circuit, a condenser in series with said spark-gap, a variable inductance in said secondary circuit between said spark gap and condenser whereby said secondary circuit may be proportioned to be charged and discharged once every half cycle of said primary alternating circuit, an aerial connected to one side of said condenser, the other side of said condenser being grounded, and a variable inductance between said condenser and the ground whereby the aerial may be tuned.

6. In a wireless telegraph transmitter, the combination, with a step-up transformer having in its primary circuit a source of alternating electro-motive-force and a sending key, of a rectifying spark-gap in said secondary circuit, a condenser in series with said spark-gap, inductance in said secondary circuit between said spark gap and the point of connection of one side of said condenser, an aerial connected to one side of said condenser, means for proportioning said primary and secondary circuits so that the latter shall be charged and discharged once every half cycle of the former, and means including a variable induction for grounding the side of said condenser away from said aerial.

7. In a wireless telegraph transmitter, the combination, with a step-up transformer having in its primary circuit a source of alternating electro-motive-force and a sending key, of a secondary circuit comprising a rectifying spark-gap which consists of a pair of spaced electrodes in the form of a blunt nosed cone and a flat plate respectively, said cone electrode having an axial bore normal to the plane of said plate electrode, and means for blowing through said bore gas at a pressure of more than fifty pounds per square inch and less than one hundred and fifty pounds per square inch, together with a condenser connected in se-

ries with said spark gap and suitable aerial connections to said condenser.

8. Wireless telegraph transmitting apparatus comprising a radiating circuit of low oscillative frequency, an exciting circuit of higher oscillative frequency than said radiating circuit, a unidirectional current gap whereby groups of impulses are fed into said radiating circuit at a frequency corresponding to that of the exciting circuit, a source of alternating electro-motive-force operatively coupled to said exciting circuit, and means for establishing and disestablishing operative connection between said source and said exciting circuit.

9. Wireless telegraph transmitting apparatus comprising a radiating circuit of low oscillative frequency and comparatively high dissipation rate, in combination with means for feeding into said radiating circuit groups of unidirectional high tension impulses, said groups being spaced apart by equal intervals which intervals are greater than the oscillative frequency of said radiating circuit.

Copies of this patent may be obtained for five cents each, by addressing the "Commissioner of Patents, Washington, D. C."

10. Process of transmitting electro-magnetic signals in the ether which consists in feeding equidistantly spaced groups of unidirectional electric impulses into a highly damped radiating circuit whose oscillative period is greater than the interval between successive groups.

11. Wireless telegraph transmitting apparatus comprising a radiating circuit of low oscillative frequency and high dissipation rate, in combination with a charging circuit containing a condenser and having a frequency higher than that of said radiating circuit, said charging circuit being electrostatically coupled to said radiating circuit, and means for governing the energization of said condenser whereby distinguishable signals may be afforded.

In testimony whereof I have affixed my signature in presence of two witnesses.

ARCHIBALD SHAW.
